UNITED STATES PATENT OFFICE

SAMUEL L. SMERK, OF CLEVELAND, OHIO

CASEMENT-WINDOW SCAFFOLD

Application filed November 27, 1928. Serial No. 322,231.

This invention relates to improvements in window scaffolds for use in the washing of windows and more particularly to a scaffold for use upon casement windows which, as is well known, are extremely difficult to wash in view of the fact that the sashes swing outwardly from the frame and it is inconvenient and dangerous for one to reach all of the panes of either sash at the outer side of the sash, and therefore the present invention has as its primary object to provide a casement window scaffold which will overcome this disadvantage and enable one to thoroughly wash casement windows without incurring any likelihood of falling from the windows.

Another object of the invention is to provide a casement window scaffold which may be readily adjusted to adapt it for anchorage upon sills of different dimensions and which will embody anchoring means of such construction that clamps and other extraneous clamping means are not required to be employed.

Another object of the invention is to provide a casement window scaffold comprising a pair of frame structures which may be readily mounted and anchored upon a casement window sill in spaced relation to each other and constitute firm supports for foot boards and guard rails which may be readily assembled with the said frame structures, the invention contemplating, in connection with the frame structures, anchoring means embodying anchoring bars which are adapted to be inserted between the opposite stiles of the window frame and the hinged sides of the two window sashes, so that displacement of the frame structures is prevented and the arrangement of the scaffold as a whole upon the window frame and the wall of the building is rendered very secure.

While the accompanying drawings and the description which is to follow, constitute a disclosure of the preferred embodiment of the invention, it will be understood that various changes may be made within the scope of what is claimed.

In the accompanying drawings:

Figure 1 is a perspective view illustrating the scaffold, embodying the invention, in-

stalled in a casement window, the sashes of the window being shown in partly open position to enable them to be readily washed by one standing upon the scaffold;

Figure 2 is a detail horizontal sectional view taken substantially on the line 2—2 of Figure 1 illustrating the manner in which the anchoring members of the side frames of the scaffold are arranged with respect to the window frame and sashes and anchored;

Figure 3 is a view partly in elevation and partly in front to rear section illustrating the scaffold mounted for use;

Figure 4 is a view partly in rear elevation and partly in section illustrating the scaffold.

The scaffold embodying the invention includes two side frame structures which are adapted to be mounted in anchoring engagement with the sill of the casement window at which the scaffold is to be located, the window frame being indicated in general by the reference letter A and the casement sashes by the reference letter B, these sashes being hingedly mounted upon the opposite stiles of the window frame, in the usual manner, so as to be adapted to be swung outwardly. The scaffold also includes foot and back boards or rails which extend between the frames, and, as illustrated in the drawing, each of the frames comprises front and rear uprights indicated respectively by the numerals 1 and 2 and a foot board supporting bar 3 which is secured by bolts or rivets 4 and 5 to the lower ends of the uprights 1 and 2, respectively, the upright 1 being secured to the bar 3 inwardly of the forward end thereof as shown in Figure 1, and the lower end of the upright 2 being secured to the outer or rear end of the said bar 3, so that the forward end portions of the bars 3, which are indicated by the numeral 6, project forwardly beyond the respective front uprights 1 and are adapted to abut against the outer surface of the wall of the building below the window sill.

Each frame structure further includes a diagonal bracing frame bar 7 having a downwardly turned rear end 8 which is disposed against one side of the respective upright 2 and through registering openings in which and in the upright is fitted a bolt 9 having a

wing nut 10' threaded thereon. From the uprights 2, the bars 7 of the two frame structures are inclined upwardly and forwardly and bolted or otherwise secured at their upper forward ends as at 10 to the upper ends of the respective front uprights 1. A brace bar 11 is secured by a bolt 12, preferably fitted with a wing nut 13, at its rear end to the respective bar 7 at a point intermediate the ends thereof and is inclined upwardly and rearwardly and secured at its other end by a bolt or other fastening element 14' to the respective upright 2 near the upper end thereof. This structure provides for a very firm relative bracing of the uprights 1 and 2 of each frame structure, with respect to each other and also with respect to the board supporting bars 3.

In order that the frame structures may be anchored with respect to the sill of the window with which they are associated, a bar 14 is provided and secured at one end by the fastening element 10 and constitutes a forward continuation of the upper end of the respective frame bracing bar 7, and this bar 14 is formed with a longitudinal series of openings 15 for a purpose which will now be made clear. An anchoring block 16 is provided in connection with each bar 14 and this block is of rectangular form and of metal and provided with a slot 17 through which the respective bar 14 is fitted, the block 16 being adjustable along the bar and held in different positions of adjustment by means of a pin 18 which is fitted through openings formed in the block 16 on a line intersecting the slot 17 and through the openings 15, interchangeably, it being understood that by withdrawing this pin the block may be slidably adjusted to any desired point along the respective bar 14.

It will now be understood, and particularly by reference to Figures 1, 2 and 3 of the drawings, that the frame structures are assembled with the window by inserting the bars 14 between the stiles of the window frame A and the hinged sides of the sashes B until the forward edges of the uprights 1 abut against the outer side of the sill of the window frame and the forward ends of the extensions 6 of the bars 3 engage against the wall of the building structure below the window sill, the blocks 16 being then fitted onto the inner end portions of the bars 14 and adjusted along the bars until they abut against a wooden cross piece 16', which is disposed at its end portions against the inner sides of the stiles of the window frame, the cross piece 16' resting at its lower end upon the upper edges of the bars 14 and the cross piece being in this manner supported in position, as shown most clearly in Figures 1, 2 and 3 of the drawings. The openings in the blocks are in registration with certain of the openings 15 in the respective bars 14, whereupon the pins 18 are fitted through the openings in the said bars

14 and blocks 16 and the blocks thus secured against displacement with respect to the said bars. Inasmuch as the forward edges of the uprights 1 abut against the outer side of the sill of the window frame and the blocks 16 abut against the inner side of the sill, and, as the projecting ends 6 of the bars 3 abut against the wall of the building structure below the sill, it will be evident that the frames are anchored in a substantial manner in upright position. The foot boards, which are indicated by the numeral 19, may then be laid upon the frame bars 3 and, as illustrated in Figures 1 and 4 of the drawings, these boards will extend between the two frame structures and be supported near their ends upon the said bars 3 of said structures.

In order to safeguard a workman standing upon the foot boards 19, guard rails 20 are provided and these rails are supported upon the rear uprights 2 by brackets 21 each of which includes an attaching portion 22 which is bolted or otherwise secured as at 23 to one side of the upright 2, each bracket further including a forwardly extending portion 24 and a right angularly upwardly extending portion 25, the brackets being secured to each upright 2 one above another and with their portions 25 spaced with respect to the forward edge of the upright and, as shown in Figure 1, the end portions of the rails 20 are disposed between the portions 25 of the uprights of the two brackets and the forward edges of the said uprights and with their lower edges resting upon the portions 24 of the said brackets.

It will be understood from the foregoing and by reference to Figure 1 of the drawings that, due to the manner in which casement window sashes are hingedly mounted, the bars 14 may be readily inserted between the stiles of the window frame and the hinged sides of the respective sashes and the sashes may be swung nearly to closed position and likewise swung open to approximately the position shown in Figure 1 thus enabling the window washer who is standing on the platform boards 19, to wash both sides of the panes of the window sashes without any inconvenience and without the danger which attends the washing of window sashes of this type without the use of a scaffold such as that embodying the invention.

In order that the scaffold structure may be supported either in the position shown in Figures 1 and 3 of the drawings or in a somewhat more elevated position, one or more openings 26 are formed in each of the front uprights 1 and when it is desired to support the scaffold in a more elevated position, the nuts upon the bolts 10 are removed and the bars 14 are separated from these bolts and disposed with their bolt openings in registration with the bolt openings 26 in the respec-

tive uprights 1 and bolts corresponding to the bolts 10 are fitted through the openings and nuts are applied thereto and tightened so as to secure the bars 14 to the uprights in position projecting forwardly at right angles therefrom.

Having thus described the invention, what I claim is:

A window washer's scaffold comprising a pair of spaced platform supporting rails, a pair of front and a pair of rear vertically disposed uprights, the pair of rear uprights being secured to the extreme outer ends of the rails, the pair of front uprights being secured to said rails inward of the inner ends thereof for engagement with the outer face of a window sill, the projecting ends of the rails engaging the outer face of the wall below the window sill, a platform on said side rails between the front and rear pairs of uprights, supporting hooks on said rear pair of uprights, outer guard rails detachably supported by the hooks, a pair of spaced upper side rails each including a horizontal window engaging supporting portion projecting beyond the inner ends of the lower rails and downwardly and outwardly inclined guard portions, means securing the upper side rails to the front pair of uprights at the point of meeting of the horizontal window engaging portions with the downwardly and outwardly inclined guard portions, means securing the extreme outer ends of the guard portions with the rear pair of uprights, anchoring blocks adjustably mounted on the horizontal window engaging portions of the side rails, and a bridge bar of polygonal shape in cross section for spanning the window at the inner side thereof and engaged by said anchor blocks.

In testimony whereof I affix my signature.

SAMUEL L. SMERK.
